UNITED STATES PATENT OFFICE.

ARNOLD DOUGLAS HEATON AND JOHN OBADIAH LANG, OF LIVERSEDGE, ENGLAND.

PRESSING OF FABRICS.

Application filed September 17, 1927, Serial No. 220,127, and in Great Britain September 18, 1926.

Our invention relates to apparatus for pressing textile fabrics, of the class in which press papers are inserted between folds of a pile of fabric which is subjected to pressure in a suitable form of press, usually a hydraulic press.

In this "flat pressing" of fabrics, it is at present the universal practice to perform the insertion and removal of the papers in apparatus separate from the press, that is to say the pile of fabric, with its inserted papers, is formed in a "papering" apparatus and is then placed into the press. After the pressing has been performed, the pile is removed from the press and returned to the papering apparatus for removal of the papers, or to enable the fabric to be "turned" that is to say to have the papers inserted in new positions so that the edges of the folds, which were left unpressed by the first operation, may be pressed by a second operation.

A plant of this description is necessarily costly and occupies considerable floor space, and whilst such a plant may be useful and practicable when large quantities of goods are to be dealt with, considerations of cost militate against its installation in comparatively small establishments.

The object of the present invention is to provide a pressing plant particularly well suited to the handling of relatively small quantities of fabrics and which, by reason of its cheapness and compactness as compared with the present plants, will warrant its installation in cases where the cost and size of one of the present plants are prohibitive.

A plant according to the invention is characterized in that a papering apparatus and a press are combined to form, as it were, a single machine, the insertion of the papers and their removal being performed on the platform of the press itself. That is, we believe, an entirely new departure in the art of fabric pressing. It not only reduces the cost of installation and the amount of floor space occupied, but it enables the labour required to be reduced to a minimum.

A plant according to the invention is illustrated in the accompanying drawing, to which reference will now be made.

In the drawing, *a* represents the table of a vertical press of suitable construction, and *b* the top plate or head of the press.

According to the invention there is disposed at each side of the press a vertically movable table *c* or *c'* to receive the press papers. These tables are shown as being capable of being moved hydraulically by means of plungers *d*, *d'* working in hydraulic cylinders *e*, *e'*, but they may be movable by rack and pinion gearing, or by worm or other gearing as may be preferred. The tables *c*, *c'* are shown as being controlled separately by handles *f*, *f'*, but they may be geared or otherwise suitably connected to move in unison, if this arrangement is preferred. The two tables are located, as shown, towards the upper end of the press, the lift of the platform or table *a* of which is determined by the maximum quantity or bulk of fabric to be treated at one operation.

Centrally of the top plate *b* of the press a roller *g* is provided over which the fabric *F* is led, such roller being detachably supported so that it may be removed when the press platform has been charged.

The permissible lift of the paper-carrying tables *c*, *c'* will preferably be such, in relation to that of the press platform, as to accommodate on each table one half of the quantity of papers required for the maximum charge of the press, the papers being inserted alternately from the two tables in the usual manner. As the depth of the paper pile decreases, the tables are gradually raised and the press platform gradually lowered, so as to keep the top of the paper piles and the top of the fabric piles substantially level and at a convenient working height for the operatives above the floor level, which is indicated at *h*.

When the desired length of fabric has been run in and papered, the top central guide roller *g* is removed and the fabric is pressed for the desired time. After pressing, the platform is lowered sufficiently to permit of the re-insertion of the central guide roller, and the end of the fabric is led over said roller and through the feed device, the latter being now run in the reverse direction. The paper-receiving tables *c*, *c'* are positioned somewhat below the level of the top of the fabric pile and as the fabric is drawn off the papers are thrown out alternately first on to one table and then on to the other, the press platform being gradually raised as the depth of the fabric pile decreases and the paper tables being

gradually lowered as the depth of the ejected papers increases.

The actual construction and arrangement of the machine will vary according to circumstances. A convenient arrangement is that illustrated in the drawing; that is to say the press foundation b' is sunk below the floor level h , and the paper tables are supported on a staging or framework k rising from the foundation, so that the working level of the tables may be at a suitable height above the floor. The paper tables may, as shown, be guided vertically at their inner sides by the tie rods b^2 , b^2 of the press, and at their outer sides by vertical guides m m' extending up from brackets or supports n n' resting on the staging k and carrying the cylinders e e' in which the plungers of the paper tables work.

We do not, however, desire to limit ourselves to this, or in fact to any, particular arrangement or construction, or to any particular means for operating the paper tables, since these may vary in many ways within the scope of and embodying the central feature of the invention, namely the provision of a flat-pressing apparatus for fabrics in which the "papering" of the fabric is done in the press itself instead of in a separate apparatus as hitherto.

The term "papers" is intended to include both ordinary press papers and also electric heating papers which, in known manner, may be interspersed at intervals in the fabric pile and connected to a suitable source of electric supply for heating the fabric prior to and during the pressing operation.

Having thus described our invention, what we claim as new and desire to secure by Letters Patent is:—

1. A fabric pressing apparatus comprising a press having a top plate and a vertically movable table below the top plate for pressing folded fabric between said table and plate, in combination with paper carrying means adjacent to the press near said top plate, so that press papers on said means may be conveniently placed in the folds of the fabric as it is folded in a pile on the table while the table is descending. 45

2. A fabric pressing apparatus according to claim 1 and including a fabric guide removably supported below said top plate in order to guide the fabric when the fabric is folded in a pile on said table and adapted to be removed when the folded fabric is to be pressed between said plate and table. 55

3. A fabric pressing apparatus comprising a press having a top plate and a vertically movable table below the top plate for pressing folded fabric between said table and plate, in combination with vertically movable paper carrying tables at opposite sides of the press near said top plate, so that press papers on the second named tables may be conveniently placed in the folds of the fabric as it is folded in a pile on the press table while said press table is descending. 60

4. A fabric pressing apparatus according to claim 3 and including the removable fabric guide below said top plate for guiding the fabric as it is folded in a pile on the press table and adapted to be removed to enable the folded fabric to be pressed between the press table and top plate. 65 70 75

In testimony whereof we affix our signatures.
